COLLAR

Application filed January 10, 1931. Serial No. 507,985.

This invention relates to soft collars for shirts, the structure being such that it may be used on separate collars, or on collars permanently united to a shirt.

5 The object of the invention is to provide an improved collar structure wherein a removable stiffening device is provided for each end of the collar to hold the same in proper shape notwithstanding its flexibility.

10 A further object of the invention is to utilize certain structural features characteristic of the usual run and stitch collar member to accommodate a separate stiffening member whereby the collar is supported and held in

15 proper position when in use, and also whereby the stiffening member may be removed without injuring the same or the collar.

A further object, more specifically, is to provide a collar having a pocket produced 20 during the manufacture of the collar, the same being formed with a slotted and turned over portion intermediate its length for receiving the stiffening member in the lower part so as to hold the lower part in place while 25 permitting the upper part to flex as a necktie is applied to the collar.

In the accompanying drawings—

Figure 1 is a fragmentary front perspective view of a shirt showing a collar disclosing an 20 embodiment of the invention applied thereto, one end of the collar being turned up for illustrating how the stiffening member is positioned;

Figure 2 is an elevation of one end of the 25 inside piece of the collar shown in Figure 1 before the same has been placed in position, the piece being illustrated with a slit;

Figure 3 is a view similar to Figure 2 but showing the portions of the ply illustrated 30 in Figure 2 turned back to produce a notch and the turned edges on the sides of the notch;

Figure 4 is a view of one end of the complete collar before it is turned, the same illustrating how the turned back portions are 35 stitched in place;

Figure 5 is a view similar to Figure 4 but showing a similar turn and illustrating the notch and pocket designed to accommodate the stiffening member;

40 Figure 6 is an enlarged sectional view

through Figure 5 on the line 6—6, the same showing the stiffening member in place;

Figure 7 is an enlarged fragmentary perspective sectional view through Figure 5 on the line 7—7;

45 Figure 8 is a perspective view of the stiffening member illustrated in Figures 1 and 6.

Referring to the accompanying drawings by numerals, 1 indicates a shirt of any desired kind, and 2 a collar permanently connected therewith. However, as far as the invention is concerned the same can be applied to soft collars not permanently secured 50 in place.

55 As shown particularly in Figures 1 and 6, a stiffening member 3 of celluloid, metal, wood or other material is adapted to be used for holding the pointed or lower portions 4 of the respective ends of the collar in the proper position. It will be noted that a section 5 is left at each end unsupported by any stiffening member. This is important in that it permits a necktie to be properly tied and adjusted without disarranging the stiffening member. If the stiffening member 3 extended 60 to the upper edge of the collar and a necktie was applied the entire front ends of the collar would be raised toward a horizontal position and this raising or elevation at the ends is objectionable because it does not present a neat and proper fitting structure. It 65 is, of course, understood that many collars have been produced heretofore wherein stiffening members have been used, to hold the ends of the collar in proper position. However, there are certain objections to each of 70 these prior structures which include the objection just mentioned of elevating the ends undesirable and, in addition, the use of buttonholes and other devices are objectionable 75 even though placed on the under side of the collar. This is true because the impression is seen through the collar during the ironing operation and consequently more or less marking the collar makes the same undesirable.

80 In the present invention there is no buttonhole and the stiffening member does not extend to the upper edge of the collar although it is arranged in the pocket 6 at each 85

- end of the collar. This pocket is constructed during the ordinary manufacture of the collar and is old and well known. The pocket 6 is formed by what is sometimes known as the run-and-stitch collar structure. However, in the manufacture of the collar in the usual way some additional steps have been used to secure the results disclosed in the drawings.
- 10 In Figure 1 the ply 7 is of the usual shape or of a desired shape provided the proper style of collar is secured. There is nothing new in the shape of the ply 7 but the slit 8 is new, said slit extending a short distance inwardly, as shown in Figure 2, said distance being in actual use about one-half inch. After this slit has been made the portions 9 and 10 are turned back, as shown in Figure 3, whereby the turned edges 11 and 12 will be presented on opposite sides of the notch 13.

What we claim is—

1. A collar having a member formed of a plurality of plies run, turned and stitched whereby a pocket is formed between the plies and between the two rows of stitching, whereby a member is run and stitched, one of said plies being slit and having the two edges thereof turned back and held in place by one of said lines of stitching, and a separate stiffening member positioned in said pocket from said slit to the end of the pocket and supported by the end of said pocket.
2. A collar formed of a plurality of plies and a plurality of rows of stitching at the respective ends forming a pocket parallel to each end, one of the plies being slit at each end, said slit being spaced downwardly from the upper edge of the collar, said last mentioned ply having the parts adjacent said slit turned back, said turned back portions being held in their turned back position by one of said lines of stitching, and a removable stiffening member arranged in said pocket extending from said turned back portions to the bottom of the collar, the portion of the collar between the slit and the upper edge being unreinforced and flexible for accommodating the bulk of a necktie when the same is in use.
